(57) **CLAIM**

The ornamental design for a table riser, as shown and described.

DESCRIPTION

FIG. 1 is a perspective view of a table riser showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown in an alternate position within its environment;

FIG. 9 is a perspective view thereof, shown in a second alternate position within its environment;

FIG. 10 is an enlarged detailed view of the boxed area labeled 10 in FIG. 1; and,

FIG. 11 is an enlarged detailed view of the boxed area labeled 11 in FIG. 2.

The broken lines in the drawings show both portions of the table riser and environmental subject matter which form no part of the claimed design.
